(57) **CLAIM**

The ornamental design for a holder for a cleaning implement, as shown and described.

DESCRIPTION

FIG. 1 is a top, left, front perspective view of a holder for a cleaning implement showing our new design;

FIG. 2 is a top, right, rear perspective view thereof;

FIG. 3 is a front elevational view thereof;

FIG. 4 is a left side elevational view thereof, the right side elevational view being a mirror image of the left side shown;

FIG. 5 is a rear elevational view thereof;

FIG. 6 is a top plan view thereof; and,

FIG. 7 is a bottom plan view thereof.

The broken-line disclosure in the views is understood to represent portions of the article in which the claimed design is embodied, but which form no part of the claimed design.
